DESIGN FOR A COVER FOR AN INSTRUMENT CASING

Donald R. Dohner, Pittsburgh, Pa., assignor to
Westinghouse Electric & Manufacturing Com-
pany, a corporation of Pennsylvania

Application December 1, 1934, Serial No. 54,218

Term of patent 7 years

To all whom it may concern:

Be it known that I, Donald R. Dohner, a citizen
of the United States, residing at Pittsburgh, in the
county of Allegheny and State of Pennsylvania,
have invented a new, original, and ornamental
Design for a Cover for an Instrument Casing, of
which the following is a specification, reference
being had to the accompanying drawing, consti-
tuting a part hereof.

Fig. 1 is a view in front elevation of the cover

for an instrument casing embodying my inven-
tion, and

Fig. 2 is a view in section taken on the line
II—II of Fig. 1.

I claim:

The ornamental design for a cover for an in-
strument casing, substantially as shown.

In testimony whereof, I have hereunto sub-
scribed my name this 22 day of Nov. 1934.

DONALD R. DOHNER.
